CLAIM

The ornamental design for a shoe-shaped tote bag, as shown and described.

DESCRIPTION

FIG. 1 is a perspective view of a shoe-shaped tote bag showing my new design, which shows the location of a single zipper upper pocket having two zipper clasps and a single-zipper back side pocket,

FIG. 2 is a front elevational view thereof;

FIG. 3 is a rear elevational view thereof showing the location of a zippered back pocket, the upper pocket and the back side pocket;

FIG. 4 is a right side elevational view thereof showing the upper pocket, the back pocket and the back side pocket;

FIG. 5 is a left side elevational view thereof showing the upper pocket, and the back pocket; and,

FIG. 6 is a bottom plan view thereof.
